E. H. LICHTENBERG

CRANE ATTACHMENT

Filed May 16, 1923

Patented Apr. 15, 1924.

1,490,117

UNITED STATES PATENT OFFICE.

ERICH H. LICHTENBERG, OF MILWAUKEE, WISCONSIN, ASSIGNOR TO KOEHRING COMPANY, OF MILWAUKEE, WISCONSIN, A CORPORATION.

CRANE ATTACHMENT.

Original application filed June 6, 1922, Serial No. 566,362. Divided and this application filed May 16, 1923. Serial No. 639,406.

To all whom it may concern:

Be it known that I, ERICH H. LICHTENBERG, a citizen of the United States, residing at Milwaukee, in the county of Milwaukee and State of Wisconsin, have invented certain new and useful Improvements in Crane Attachments, of which the following is a specification.

This application is a division of my pending application Serial #566,362, filed June 6, 1922, and the subject of the invention is a peculiar mounting for a crane or derrick attachment for large machines of a portable type.

15 In its practical adaptation my invention comprises a crane consisting of a mast, a boom connected therewith to swing laterally, suitable hoisting mechanism for a load adapted to be supported from the boom. 20 This crane is designed to be used upon concrete paving machines, or similar large machines that are supported by wheels or endless traction devices so as to travel from place to place, and progress as certain work 25 performed thereby proceeds. Owing to the heavy loads designed to be handled by the crane or derrick attachment, my invention resides in the provision of a special mounting or stepping of the mast of the crane

30 upon the frame of a main traction member by which the machine with which the crane attachment is used, is mounted to travel. As the body frame of the large machine carrying the derrick attachment is usually 35 adapted for tilting movement as when a three-point suspension principle of construction is employed, it will be apparent that with my crane attachment mounted or stepped directly upon one of the traction

40 members, by which I mean the supporting structure of said traction member, enables the weight of the crane and its load to be carried over and by the surface on which the main machine travels, without being 45 transmitted thereto thru a supporting means upon the body frame of the main machine itself. A greater stability of the main machine and the crane are thus obtained by the invention.

50 In the accompanying drawing;

Figure 1 is a side view showing a crane attachment embodying the invention.

Figure 2 is a front view of the truck and traction devices of the machine supporting the crane showing more fully how the latter

is stepped or mounted upon one of the multi-planes or endless traction members.

It is not deemed necessary to describe in detail the machine in conjunction with which my improvements are employed. It suffices to know that my machine comprises a frame or body 1 mounted on traction multiplanes 2, preferably by a rocker bearing 3, seen best in Fig. 2. A loading skip 4 for raising the concrete aggregates and charging them into a concrete mixer, not shown, is used. The end of the machine equipped with the skip 4 has the crane and grappling apparatus of my invention applied thereto. This crane includes the mast 5 which is stepped upon an arm 6 pivoted to the frame 1 at 7, and directly supported upon a bracket 8 carried by one of the multiplanes 2.

The mast 5 is equipped with the boom 9 braced by a guy rod 10, and at the base of the mast 5 is a winding drum 11, the cable 12 of which winds about in opposite directions and leads off to some suitable power driving means which enables the mast 5 to be driven positively in either of opposite 80 rotative movements, for swinging the boom 9 in corresponding directions to carry a batch box from an industrial car to the skip 4, and back again.

The machines of my invention, as generally depicted in Figure 1, are so large, having a capacity as large as thirty-two cubic feet, that power mechanism is necessary for preferred operation of machines of such size.

It is not believed necessary for the purposes of this description, to set forth in detail the hoisting mechanism and the batch box apparatus which are illustrated as used in conjunction with my crane attachment. While a special type of such mechanism is employed, as illustrated, it will be understood that any conventional hoisting and batch box apparatus might be employed within the purview of the present invention, because the latter involves primarily the mounting of the crane attachment itself rather than any specific hoisting or other apparatus that may be used in connection therewith.

It is notable from the foregoing that since the crane is practically supported, with any load thereon, directly by the multiplane or other traction device, which may be used in connection therewith, and liability of over-balancing of the frame of the main ma-

chine in the use of my crane is entirely avoided. If the condition of the surface over which the main machine is traveling is rough, it will be seen that as the traction member 2 travels up and down the crane attachment moves in correspondence therewith, and to a certain extent independently of the main frame 1, owing to the provision of the arm 6 pivoted to said frame 1 at the point 7. Of course, the specific method of connecting the crane with the main frame and with the traction member, while believed to be new, may be modified and varied within the scope of the invention and that of the claims annexed hereto.

Having thus described my invention, what I claim as new and desire to secure by Letters Patent, is:

1. In a machine of the class described, the combination of a portable support comprising a frame, traction devices on which the frame is mounted, and a crane comprising a mast supported on said traction devices and an offstanding boom connected with the mast, the crane and any load lifted thereby being directly carried by the traction device.

2. In a machine of the class described, the combination of a portable support comprising a frame and a pair of multiplanes supporting said frame at opposite side portions thereof, a rocker bearing intermediate an end of the frame and the multiplane supporting means, and a crane mounted upon the support and comprising a mast and a boom and a bracket carried by one of the multiplanes and supporting the said crane thereon so that the weight of the crane and its load are directly carried by the said multiplane, the crane being located at the end of the support equipped with the rocker bearing connection with the multiplane traction means.

3. In combination, a main machine comprising a body construction, supporting traction devices for said main frame adapted to have movement independently of the main frame, and a crane supported by one of said traction devices.

4. In combination, a machine comprising a main body frame, traction devices on which the weight of the body frame is supported, and by which said machine is caused to travel for the performance of its work, and a crane connected with the body frame of the machine and stepped upon one of the said traction devices so that its weight and that of any load carried thereon will be primarily received upon said traction device and not upon the main body frame of the machine.

5. In combination, a machine comprising a main body frame, traveling traction devices on which the weight of the body frame is supported by which said machine is enabled to travel for the performance of its

work and movable independently of their traveling motion relatively to the main frame, and a crane connected with the body frame of the machine and stepped upon one of the said traction devices so that its weight and that of any load carried thereon will be primarily received upon said traction device and not upon the main body frame of the machine, the connection between the crane and the body frame comprising an arm attached to the crane and having a pivotal connection with the body frame to permit of said independent movement of the traction devices.

6. In combination, a machine comprising a main body frame, traction devices on which the weight of the body frame is supported, and by which said machine is caused to travel for the performance of its work, and a crane connected with the body frame of the machine and stepped upon one of the said traction devices so that its weight and that of any load carried thereon will be primarily received upon said traction device and not upon the main body frame of the machine, the connection between the crane and the body frame comprising an arm attached to the crane and having a pivotal connection with the body frame, the traction devices aforesaid having a single point connection with the body frame at a point adjacent to the point of connection of the said arm with said frame.

7. A machine comprising a body frame, traction devices supporting the same and upon which the body frame is adapted to be moved whereby a portable construction is obtained, a connection between the body frame and said traction devices enabling movement of the traction devices independently of the movement of the body frame, and a crane stepped upon one of the traction devices and having connection with the body frame aforesaid.

8. A machine comprising a body frame, traction devices supporting the same and upon which the body frame is adapted to be moved to establish a portable construction, a connection between the body frame and said traction devices enabling movement of the traction devices independently of the movement of the body frame, and a crane stepped upon one of the traction devices and having connection with the body frame aforesaid, the connection between the traction devices and the body frame being a horizontal pivot between the sides of the body frame and the connection between the crane and the body frame being a horizontal pivotal connection located substantially in the same vertical plane as the pivotal connection between the traction devices and the body frame.

9. In combination, a main machine comprising a body frame, endless traction de-

vices supporting said frame and by which the machine may be propelled, a single point pivotal connection between the ends of the body frame, an axle connecting the endless traction devices and to which the said single point pivotal connection aforesaid is attached, said traction devices comprising a traction frame and an endless traction member operating about said frame, a bracket attached to said traction frame, a crane attachment for the main machine comprising

a mast, a boom, a connection between the upper portion of said mast and the frame of the machine, an arm pivoted to the body frame of said machine, and supported by 15 said bracket on the traction frame, means whereby the mast is stepped upon said arm, and a pivotal connection between the said arm and said body frame.

In testimony whereof I affix my signature.

ERICH H. LICHTENBERG.
